R. CLASSEN

SOLENOID OPERATING MECHANISM

Filed Sept. 7, 1923

Fig. 1.

UNITED STATES PATENT OFFICE.

RICHARD CLASSEN, OF SCHENECTADY, NEW YORK, ASSIGNOR TO GENERAL ELECTRIC COMPANY, A CORPORATION OF NEW YORK.

SOLENOID-OPERATING MECHANISM.

Application filed September 7, 1923. Serial No. 681,525.

To all whom it may concern:

Be it known that I, RICHARD CLASSEN, a citizen of the United States, residing at Schenectady, in the county of Schenectady and State of New York, have invented certain new and useful Improvements in Solenoid-Operating Mechanisms, of which the following is a specification.

My invention relates to electric switches of the solenoid operated type.

Where switches of this type having relatively large capacity have been constructed with a plurality of operating solenoids arranged side by side, each solenoid heretofore has been provided with its own toggle and tripping mechanism. Difficulties have arisen with switches so constructed due in the most part to the failure of the several toggle and tripping mechanisms to function in synchronism after the switch has been for some time in actual service. The object of the present invention is to provide an improved and simplified switch operating and controlling mechanism, and one which shall not be subject to the aforesaid difficulties.

My invention will be better understood by reference to the accompanying specification and drawings and its scope will be pointed out in the appended claims.

Fig. 1 is a view partly in section of an oil switch and the operative mechanism therefor involving my invention, the switch being in its closed position.

Fig. 2 is a top view of the solenoid mechanism shown in Fig. 1.

Fig. 3 is a fragmentary view on an enlarged scale of the solenoid mechanism and tripping devices when the switch is in open position, and

Fig. 4 is another fragmentary view of the tripping devices, as in Fig. 1, but drawn to a still larger scale.

Referring to the drawing 1 represents an oil switch of the downward break type having a pair of stationary contacts 2 and 3 which are engaged by a pair of movable contacts carried at opposite ends of a cross arm 4. The arm 4 is raised and lowered to operate the switch by means of a rod 5 which is pivoted to the end of a lever 6. This lever is operatively connected to the push rod 8 by means of a bellcrank 7, rod 9 and toggle links 9', the latter being underset when the switch is closed and held in

that position by other toggle mechanism to be described later.

The force for operating the switch is furnished by four solenoids 10, 11, 12 and 13 arranged in two groups, each comprising two solenoids in tandem as shown. Each solenoid is provided with the usual core section 14 and with the plunger 15, and the two plungers of the solenoids forming a group are joined together by a push rod 16. The upper portion of each push rod 16 passes through the frame 17 and is provided with a head 18 between which and the frame is a comparatively heavy coil spring 19. At opposite ends of the frame 17 are bifurcated supports 20 and 21 for carrying the two main operating levers 22 and 23, respectively. The former is pivoted directly to the support 20 while the latter is pivoted to the support 21 through a link 24 in order to allow it to have the necessary longitudinal movement. Lever 23 is provided with a socket at its outer end to detachably receive a handle 25 by which the switch may be manually operated. The levers 22 and 23 are pivoted together at their adjacent ends, and by the same pivot pin are connected to the lower end of the rod 8. Each lever also carries a roller 27 against which bears the head 18 of the push rod 16 when the switch is being closed.

Toggle links 28 and 29 connect the pin joining the levers 22 and 23 with a shaft 30 journaled in the frame 17. Lower link 29 and crank 31 are made fast to the shaft 30, a pivot pin at the outer end of the crank being in alignment with the pin connecting together the toggle links 28 and 29. A spring 32 is tensioned between this latter pin and the pin joining the ends of levers 22 and 23, the opening at the upper end of link 28 being somewhat elongated to provide a resilient lost motion connection at this point to relieve the strain, or shock, on the toggle upon closing the switch.

When the switch is closed, as shown by Fig. 1, buckling of the toggle links 28 and 29 is prevented by another toggle comprising links 34 and 35, the former having an extension provided with a roller. This roller, as seen more clearly in Fig. 4, hooks under a catch 37 which is pivoted at 38 to a rocking member 39. This member is pivotally supported, as shown on the frame 17, being positively restrained from movement

in a clockwise direction by a foot 40 and being resiliently restrained from movement in the opposite direction by a spring 41. A latch 42, pivotally mounted on member 39 engages a portion of the catch 37 to hold the same in a position to retain the roller on the extension of link 34. The stem 43 of an auxiliary solenoid enclosed in a housing 44 raises the tail of the latch 42 when the solenoid is energized to release the catch 37, thus tripping open the switch. A post 45 limits the downward movement of the link 35 when the switch is being closed.

From the above description it will be apparent that when the switch is closed, the parts being in the position illustrated by Fig. 1, an upward movement of the stem 43 of the auxiliary solenoid will release the latch 42, permitting the catch 37 to rotate sufficiently to release the roller carried by the end of toggle link 34. Buckling of this toggle in turn permits toggle links 28 and 29 to buckle and the levers 22 and 23, together with the push rod 8, to drop whence the switch opens. The parts then assume the position shown in Fig. 3. The springs 19 function to cushion the downward movement of the plungers 15 when the solenoids are deenergized.

30 Closing of the switch is effected by the energization of the solenoids 10, 11, 12 and 13, whereupon the plunger rods 16, in ascending, rock the levers 22 and 23 to raise the push rod 8. Upward movement is therefore given to the cross-arm 4 carrying the movable switch contacts through the intervening mechanism shown. As the toggle links 34 and 35 move toward their straightened position during the closing movement 40 of the switch, the roller on the end of link 34 rolls down the inclined upper portion of the member 39, causing the member to rock against the spring 41 until the roller passes over the point of the catch 37, clockwise movement of the catch 37 being prevented by a stop shown in dotted lines in Fig. 4.

While I have described only one embodiment of my invention, I do not wish to be limited to the particular form shown and described as it will be apparent that many modifications therein may be made without departing from the scope of my invention as set forth in the appended claims.

What I claim as new and desire to secure by Letters Patent of the United States, is:—

1. In an electric switch, a plurality of solenoids, a lever adapted to be actuated by each of said solenoids, means for connecting

together corresponding portions of said levers, and a tripping mechanism operatively connected to said means to control the movement of said levers in one direction. 60

2. In an electric switch, a plurality of solenoids each having a plunger, a lever for each of said solenoids adapted to be moved in one direction by the corresponding plunger, means operatively connecting said levers together, and a single tripping mechanism for controlling the movement of said levers in the opposite direction. 65 70

3. In an electric switch a frame, a pair of solenoids secured side by side thereto, a pair of inter-connected levers mounted on said frame and each adapted to be actuated by one of said solenoids, a switch contact operating rod operatively connected to said levers, and a single tripping mechanism also operatively connected to said levers. 75

4. In an electric switch, a frame, a pair of solenoids secured thereto, a plunger and an operating rod for each of said solenoids, a pair of levers pivotally mounted on said frame each adapted to be engaged by one of said operating rods, a pin connecting together said levers, a toggle mechanism between said pin and said frame, and means for releasing said toggle mechanism. 80 85

5. In an electric switch having a movable switch contact, a frame, a pair of oppositely arranged levers fulcrumed on said frame, a solenoid for each of said levers, means connecting corresponding ends of said levers, means operatively connecting said switch contact with said first means, and a single releasable toggle mechanism between said first means and said frame. 90 95

6. In an electric switch having a stationary contact and a cooperating movable contact biased to open circuit position, a frame, a pair of solenoids arranged side by side and secured to said frame, a plunger for each of said solenoids having a rod extending through said frame, a lever for each of said solenoids each adapted to be actuated by one of said rods, a pin connecting together corresponding ends of said levers, a connection between said pin and said movable contact, a toggle mechanism between said connecting pin and said frame, and a tripping device for releasing said toggle mechanism to permit said movable contact to return to open circuit position. 100 105 110

In witness whereof, I hereunto set my hand this 6th day of September, 1923.

RICHARD CLASSEN.
